UNITED STATES PATENT OFFICE

STANLEY THOMAS HARVEY, OF MILL VALLEY, CALIFORNIA

AMUSEMENT DEVICE

Application filed May 13, 1929. Serial No. 362,723.

My invention relates to improvements in amusement devices, and it consists in the combinations, constructions, and arrangements hereinafter described and claimed.

It is possible to make people believe that they are moving even though in fact they themselves are not moving, but the objects at which they are looking are in movement. With this thought in view, I have devised an amusement device which will make people actually believe that they are flying although in reality the device does not leave the ground.

I accomplish this by removing all objects upon which the eye can focus that might inform the person that he was not actually flying. I make the person believe that he is flying by first constructing a theater that will resemble the cabin of a passenger-carrying airplane. The floor of the theater is moved in a predetermined manner so as to simulate actual flying.

In addition to this, I place a "pilot" at the front of the theater for the purpose of manipulating the controls for guiding the would-be airplane. On each side of the pilot, I place the wings of an airplane and mount propellers in front of the wings, which will make a droning noise in much the same manner as airplane engines. These propellers will also create a breeze which will whip by the spectators' faces, thus enhancing the flying sensation.

Positioned at the front of the theater is a screen on which moving pictures are thrown. These pictures have previously been taken during actual flying or from camouflaged scenes. The theater is darkened so that only the screen is visible, and the pilot and the pictures can be so portrayed as to give the effect of flying. Different pictures may be shown, for example, flights across the ocean, over the North or South Pole, sightseeing trips over cities or war pictures in which actual fighting takes place between airplanes or dirigibles.

Other objects and advantages will appear in the following specification, and the novel features of the device will be particularly pointed out in the appended claims.

My invention is illustrated in the accompanying drawings forming a part of this application, in which

Figure 1 is a top plan view of the device, portions being shown in section;

Figure 2 is a longitudinal section through the device;

Figure 3 is a front elevation;

Figure 4 is a section through a portion of the device; and

Figure 5 is a section through another portion of the device.

In carrying out my invention, I provide a building, indicated generally at 1, this building being of any shape desired. I found that a shape, as shown in Figures 1 and 3, will make more of an appeal to the amusement-loving public than other shapes. The side walls 2 of the building may be used for pictorial illustrations showing airplanes fighting one another, sight-seeing trips over certain parts of the world, etc.

The building is provided with two entrances 3, (see Figure 1). Either one of these entrances may be used or both may be used, this depending upon the size of the crowd to be handled. Disposed adjacent to each entrance are ticket booths 4, (see Figure 3).

Within the building I dispose a circular enclosure 5 and in the enclosure, I rotatably mount a theater 6. The wall of the enclosure 5 has an entrance opening 7 which may be closed by a door, if desired. The wall 8 of the theater 6 has an entrance opening 9 that is designed to be brought into registration with the opening 7 for permitting people to walk on to the floor 10 of the theater. An inclined passageway 11 leads from the entrance 3 to the door opening 7.

If both entrances 3 are used, the people passing through the rear entrance will be directed through a door opening 12 and then to the door opening 7. When only the front entrance is used, the door opening 12 is closed.

The floor 10 is rotatably and pivotally supported at its center by a hemisphere 13 which is seated in a hemispherical recess 14 in a

support 15. The support is carried by a foundation 16, (see Figure 2).

The periphery of the floor 10 is supported at two places by wheels 17 and 18, shown in dotted lines in Figure 1. These two wheels are disposed far enough apart to cooperate with the central support for forming a three-point support. The floor 1 may be weighted at the side nearest the wheels so as to keep the wheels resting upon a circular track 19, (see Figure 2). This weight may be sufficient to counter-balance the weight of any persons within the theater, regardless of where they are standing or sitting.

As a precaution against the tilting of the floor 10 at too much of an angle, I provide a retaining rail 20 that is disposed above the circular track or supporting rail 19. The wheels 17 and 18 normally do not contact with the retaining rail 20, but they will contact with this rail should the floor 10 be suddenly forced upwardly adjacent to these wheels for any unknown reason and the wheels engaging with the retaining rail would prevent further movement.

I have found that a three-point support is sufficient for the floor and that the rail 19 may be curved so as to have a vertical rise and fall. This curve is clearly shown in Figure 2. The rail 20 has a similar curve. The wheel 17 is a driving wheel, and this engages with the supporting rail 19 and causes the entire theater 6 to revolve. This movement, of course, will be felt by the persons in the seats 21, and the undulations in the track 19 will cause the floor to tilt laterally, simulating the slight rocking of an airplane while flying. A single wheel 17 is not sufficient to give the lateral rocking effect. Two wheels spaced apart, as shown in Figure 1, will produce this effect.

The means for rotating the wheel 17 may comprise any mechanism desired. I have shown an electric motor 22, (see Figure 5), this motor driving a worm 23 that meshes with a worm gear 24, the latter being mounted upon the shaft 25 that carries the wheel 17. One terminal of the motor is grounded, while the other terminal has a wire 26 that extends into a cylinder 27, (see Figure 4), and has its end secured to a piston 28. The piston carries a piston rod 29, which in turn supports a roller 30 that rides upon a circular conductor rail 31. A spring 32, disposed within the cylinder 27, urges the piston 28 downwardly and keeps the roller 30 in contact with the rail at all times. A wire 33 leads from the rail 31 to the source of current. In Figure 2 I have shown the wire 33 as extending into a conduit 34, the conduit extending to the source of current. The stroke of the piston rod 29 is long enough and the length of the roller 30 is sufficient to permit the floor 10 to swing into various angular positions during

its travel and still have the wire 33 electrically connected to the wire 26.

If desired, a spring box 35, (see Figure 5), may be disposed in the cockpit 36 so that the "pilot" 37, (see Figure 2), sitting on the seat 38, may control the movement of the theater 6.

To carry out the realism of actual flying, I dispose airplane wings 39, shown by the dotted lines in Figure 1, at the front of the theater. The framework 40, (see Figures 2 and 5), surrounding the cockpit 36, extends downwardly at an angle and merges into the aisle 41, (see Figure 1), in the theater. I dispose two propellers 42 on each side of the cockpit and these are actuated by electric motors 43 or other suitable means. The propellers will not only make a noise simulating the propellers of an airplane, but will also create a draft which will flow past the spectators and enhance the illusion of flying.

At the front of the theater, I dispose a screen 44, which, if desired, may be framed to represent windows in the cabin. A moving picture projection machine 45, (see Figure 2), is disposed diametrically opposite the screen 44 and will throw pictures upon the screen 44. As stated in the first part of the specification, these pictures may be of an infinite variety depicting flights across oceans, sight-seeing trips, actual airplane fights, etc. For example, a fight with a dirigible might show the dirigible as a small speck far off in the distance, this speck gradually growing larger until the would-be airplane was within striking distance. The pictures could then be made to show the airplane zooming around the dirigible, jockeying for a vital position before firing.

Machine guns might be disposed adjacent to the pilot seat with blank cartridges, and these could be set going to make the entire effect more realistic. The guns from the dirigible might be shown trained upon the airplane and firing point blank at it. This is merely an example showing how realistic the device could be made to function.

Nearing the end of the reel, the "pilot" would slow down the movement of the theater 6 and would bring it to a stop with the opening 9 registering with an exit opening 46, (see Figure 1), in the circular enclosure 5. The people would file out through the central aisle 41, pass through the aligned openings 9 and 46, and then proceed down stairs 47 and out through the exit openings 48 in the building 1.

After the people have left the theater, it may be rotated so as to again bring the opening 9 into registration with the opening 7, 125 so as to permit people to enter for the next show.

Although I have shown and described one embodiment of my invention, it is to be understood that the same is susceptible of vari- 130

ous changes, and I reserve the right to employ such changes as may come within the scope of the appended claims.

I claim:

- 5 1. An amusement device comprising a building, a support, an entirely enclosed theater disposed within said building and having a universal connection with said support, means for rotating and tilting the entire theater as a unit in a predetermined manner, and means for projecting pictures of flying within said theater and cooperating with the movement of said theater for creating the illusion of flying.
- 10 2. An amusement device comprising a building having a circular enclosure, an entirely enclosed theater movably disposed within said enclosure, said enclosure and the theater having door openings adapted to register with one another, when the theater comes to rest, means for projecting pictures of flying, within said theater, and means for rotating and tilting said theater as a unit during the showing of the pictures.
- 15 3. An amusement device comprising an entirely enclosed theater, an airplane fuselage and wings disposed at the front of the theater, propellers mounted in front of the wings, a screen disposed in front of the propellers, means for projecting pictures on the screen, and means for imparting a circular movement to the theater as a unit and for causing it to rise and fall during this movement.
- 20 4. An amusement device comprising a support, a circular entirely enclosed theater having a universal connection with the support, a circular track slightly larger in diameter than the theater and having undulations therein, wheels carried by the theater and riding upon the track, means for driving the wheels for causing a rotation and tilting of said theater, and means for projecting moving pictures during the movement of the theater.
- 25 5. An amusement device comprising a support, a circular entirely enclosed theater having a universal connection with the support, a circular track slightly larger in diameter than the theater and having undulations therein, wheels carried by the theater and riding upon the track, means for driving the wheels for causing a rotation and tilting of said theater, means for showing pictures of flying, within said theater during the movement of said theater, propellers disposed within the theater, and means for rotating the propellers for creating the illusion of flying.
- 30 6. A device for creating the illusion of flying and comprising a support, a circular entirely enclosed theater having a universal connection with said support, a building housing the theater, a circular track encircling the support and being slightly larger in diameter than the diameter of the theater, wheels for supporting a part of the theater removed from the universal connection and traveling on said track, means for driving the wheels, said theater and building having door openings adapted to register, and means for projecting moving pictures within the theater enclosure.
- 35 7. In a device for simulating flying, a disc-shaped floor, a support for the center of the floor giving it a universal movement, a two point support for the periphery of the floor consisting of an undulating track having a diameter substantially the same as the diameter of the floor and wheels riding on the track and supporting the floor at the two points, the entire periphery of the floor being free to dip in any direction as guided by the wheels, and means for slowly rotating the floor.
- 40 8. In a device for simulating flying, a disc-shaped floor, a central support for the floor and having a universal connection therewith, means for slowly rotating the floor, and means for engaging with the floor at two points on its periphery for causing the floor to slowly dip in various directions as it turns for giving the sensation of actual flying.
- 45 9. In a device for simulating flying, a disc-shaped floor, a central support for the floor and having a universal connection therewith, means for slowly rotating the floor, means for engaging with the floor at two points on its periphery for causing the floor to slowly dip in various directions as it turns, and means for projecting moving pictures on a screen while the floor is dipping and turning.
- 50 10. A device for creating the illusion of flying and comprising an entirely enclosed theater designed to be rotated as a unit, means for rotating the theater, means for causing the theater to tilt at various angles while rotating to simulate actual flying, a screen disposed within and at the front of the theater, means for projecting moving pictures on the screen, and rotatable propellers disposed adjacent to the screen for adding to the illusion of flying.
